UNITED STATES PATENT OFFICE.

HARRY S. MOSES, OF HUBBARD WOODS, ILLINOIS.

UNDERGARMENT.

1,349,976.

Specification of Letters Patent. Patented Aug. 17, 1920.

Application filed August 14, 1919. Serial No. 317,443.

To all whom it may concern:

Be it known that I, HARRY S. MOSES, a citizen of the United States, residing at Hubbard Woods, in the county of Cook and 5 State of Illinois, have invented a new and useful Improvement in Undergarments, of which the following is a specification.

My invention relates more particularly to undergarments of the so-called union-suit 10 type and particularly to such type of garments for women's wear.

My primary object is to provide a buttonless garment of the type referred to which may be made from flat-piece fabric, 15 as distinguished from tubular knitted fabric, be smooth fitting and be comfortably worn.

Referring to the accompanying drawings—

Figure 1 is a front view of a garment constructed in accordance with my invention. Fig. 2 is a rear view thereof. Fig. 3 is a front view of the same with certain parts broken away and others deflected, the better to illustrate certain details of the garment; 25 and Figs. 4 to 9, inclusive, plan views, of reduced size, of the sections (except the yieldable section) from which the garment is formed, Fig. 4 showing the front of the body-portion, Fig. 5, the back thereof, Fig. 30 6, the front portions of the leg-portions of the garment, Fig. 7, the rear portions of the leg-portions, and Figs. 8 and 9, gussets used with the pieces of Figs. 6 and 7 for forming the leg-portions.

35 My improved undergarment is formed of pieces of flat fabric, such for example as muslin or any other suitable material as distinguished from tubular fabric, and in accordance with the preferred form shown is 40 formed of the sections 10 to 17, inclusive, cut from the fabric and shown in Figs. 4 to 9, inclusive, and in addition a strip 18 of yieldable material which may be ribbed knitted goods.

In forming the garment the front and rear sections 10 and 11 are sewed together at their lateral edges, or in other words at the side portions of the garment, the strip 18 is sewed at its upper edge to the lower edge 19 of the section 11 and at its ends to the opposite lateral edges of the section 10, the gusset 16 is sewed along its edge 20 to the edge 21 of the section 14 and at its end 22 to the front section 12 at 23, the gusset 17 is sewed along its edge 24 to the edge 25 of the section 15 and at its end 26 to the

front section 13 at 27, the edges 28 and 29 of the sections 14 and 15, respectively, are sewed to the edges 30 and 31 respectively, of the sections 12 and 13, the sections 12 and 13 are sewed to the sections 14 and 15 along their outer edges 32 to 35, inclusive, respectively, the sections 14 and 15 extending upwardly beyond the sections 12 and 13 as shown, the sections 14 and 15 at those portions of their outer edges 34 and 35 which extend above the sections 12 and 13 being sewed to the lower portions of the lateral edges of the section 10 which they overlap. At the front of the garment the edges 36 and 37 of the sections 12 and 13 slightly overlap and in such condition are sewed together between the points *x* and *y*, these sections being secured along their upper edges to the lower edge of the front section 10. 75 At the back of the garment the sections 14 and 15 and gussets 16 and 17, constituting the crotch-forming members connected together as stated, overlap as shown and in this condition are secured to the lower edge 80 of the strip 18 of yieldable material, it being understood that by this construction the crotch portion of the garment is formed of the overlapping spreadable parts or flaps, as shown, forming the opening of this portion 85 of the garment.

In a garment so formed the front section of the body-portion is unsevered and seamless down the front of the garment and the use of buttons which are objectionable especially where they underlie the corset, is avoided. The garment smoothly fits the wearer and does not present any seams at those portions thereof where discomfort to the wearer would result.

90 In the particular construction shown the body-portion of the garment is provided with shoulder-straps for supporting the garment and a draw-string for gathering the upper portion of the garment about the body 100 of the wearer.

While I have illustrated and described a particular construction embodying my invention I do not wish to be understood as intending to limit it thereto as the same may 105 be variously modified and altered without departing from the spirit of my invention.

What I claim as new and desire to secure by Letters Patent is:

An undergarment of the union-suit type 110 comprising a body-portion formed of front and back sections sewed together at their

side edges, the front section being formed from a single unsevered unitary piece of relatively inelastic fabric, leg portions the front of each being formed from a single piece and having their upper edges secured to the lower edge of the front body section, and overlapping crotch-forming members

10 forming an opening and secured to the inner edges of said leg portions, the free edges of said crotch-forming members being substantially parallel from the apex of the crotch with the lower portion of said side seams.

HARRY S. MOSES.
